UNITED STATES PATENT OFFICE

WILLIAM A. BOHNE, OF PHILADELPHIA, PENNSYLVANIA, ASSIGNOR TO E. F. HOUGHTON & COMPANY, OF PHILADELPHIA, PENNSYLVANIA, A CORPORATION OF PENNSYLVANIA

MACHINE FOR FORMING LOOM PICKERS

Application filed April 9, 1929. Serial No. 353,754.

This invention relates to an improvement in the method of forming loom pickers and, more particularly, refers to a new and novel method of making such articles from leather, or other material adapted to be compressed and formed as hereinafter described.

In forming loom pickers made of leather or other similar material, it is customary to build up the structure of the picker from suitably cut leather pieces by positioning such material in their relative places and then securing them temporarily in such proper relationship by means of a nail or tack. The element is immersed in a solution of hot wax or other impregnating compound until perfectly flexible and pliable and subsequently positioned in a mould of suitable shape where pressure is applied. When the element has been pressed into shape, the mould is cooled, by water or other cooling means, thus solidifying the wax or suitable impregnating compound used. A picker formed in this manner has a large degree of hardness and stability due, first, to the pressure applied to the moulding machine and, second, to the impregnating wax or other solution which has solidified by cooling and thus rendered the leather extremely stiff. As a final operation, it has been customary to firmly rivet together the picker, this being an additional securing means, inasmuch as the tacks which were first used were only for the purpose of temporarily holding together the structure as initially positioned.

It is the principal object of this invention to provide suitable and economical means for efficiently and automatically moulding and cooling a plurality of loom pickers in one operation, whereby a great saving of time and increase in the quality of picker is effected.

The invention further resides in the provision of novel apparatus for carrying out my invention as hereinafter described taken in connection with the following drawings, of which

Fig. 1 is a plan view of the entire apparatus;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a side view of Fig. 1 showing particularly in section the pressure and waste-water control valves;

Fig. 6 is a view showing the detail construction of the mould; and

Fig. 7 is a view showing the completed moulded unit.

Referring to the drawings, Fig. 1 represents a perfected form of apparatus whereby my invention may be practiced which consists of a rectangular cast-iron cooling basin or trough 1 supported on any suitable stand 45, which is reinforced on the sides by the rods 5 bolted to projections 6 which are integral with the basin. Arranged in the four corners of the basin and suitably attached thereto, as will be herein described, are the moulds and cooperating apparatus. It is to be noted that each of the four moulds are identical in characteristics and equipment, therefore, for the purpose of brevity and clarity, we will undertake to describe only one of the particular mould units, inasmuch as the description will apply to each one similarly.

The moulds, as shown in Figs. 1 and 6, are composed of the side piece 7 forming one side of the mould, and arranged to be fastened to the basin by means of bolts 8, 8, the pressure applying members 9 and 10, actuated by the pistons 11 and 12 and fastened thereto by the set screws 13, 13, the base 14 provided with an aperture 14' to receive the filler member 18, and attached thereto a shaping piece 15 secured and restrained to the base by the bolt 16 and dowel pin 17. The base 14 is further provided with holes drilled as indicated to receive the springs 43, as shown in Fig. 3, which functions to disengage the base 14 and the formed picker from the stationary side piece 7 of the mould when the mould is opened. The top piece 19 of the mould is provided with an aperture 19' adapted to receive the filler member 18 and it is so shaped as to provide flanges 23 which cooperate with

grooves 24 in the side pieces 7 and 9, respectively, so that when the mould is closed, they provide a self-adjusting clamping means to effectively restrain the top piece in position 103.

and permit pressure to be applied in all directions against the picker. The shaping piece 15 abuts against the cast-iron basin as indicated in Fig. 4 along the side 44 and thus effects a stop for the action of the pressure exerted by the side piece 10 which is actuated by the piston 12. A bolt 20 offers a holding means for the springs 21 which are fastened, for convenience, at their other ends to the pipes 22. Referring particularly to Figs. 1 and 2, it may be noted that the moulds are fastened to the four corners of the basin, the side pieces 7 being securely bolted to the basin by means of the bolts 8, 8.

Cylinders 25, as shown in Figs. 3 and 4, are identical in construction and are composed of a cylinder wall 26 provided with suitable packing glands and packing 27. They are securely bolted to the basin by means of bolts 28 and are positioned midway between the moulds, thus permitting the pistons 11 and 12 to exert pressure in a horizontal direction against the side pieces 9 and 10. The pressure pipes 22 are provided with check valves 29 for the purpose of regulating the pressure on each of the four cylinders. The side pieces 9 and 10, which are actuated by the pistons 11 and 12, are normally positioned away from the mould when there is no pressure on the cylinder by reason of the restraining action of the springs 21 and 30. The springs 21 are conveniently fastened to the members 10 and the pipes, as described heretofore, the springs 30 are fastened to the members 10 by means of the eye-bolts 31. It is to be noted that the side pieces 9 require two springs, this provision being made due to the length of the side piece, and that these springs are not fastened rigidly to the basin, as in the case of the springs 21, but resiliently join the side pieces 9 of the adjacent moulds.

Referring to Figs. 1 and 2 particularly, the cast-iron cooling basin is provided with a waste pipe 32 which is arranged flush with the bottom of the basin which is slightly tapered toward this point and adapted to carry away all of the waste cooling water and oil in the basin. The water supply pipe 33 is arranged to be controlled by the valve 34 and is provided with an elbow 35 inside of the basin whereby the water may enter the basin without splashing. The overflow pipe 36 is definitely arranged to limit the water level in the basin to a predetermined height and is always connected so as to carry away any waste water. Referring to Figs. 2 and 5, it may be noted that the pressure pipes 22 are connected to the valve 37 which is arranged, when the handle 38 is in its up position, to join the pressure pipe 39 directly to pipes 22 and, therefrom to the cylinders 25. The linkage 40 is provided to actuate valve 41 simultaneously with valve 37 whereby the valve 41 closes the waste pipe 32, thus allowing the water level to rise in the basin

to the top of the waste pipe 36. When the handle 38 is in the down position, the valve 37 is arranged to connect the pipes 22 to the exhaust pipe 42 and the cooperating means 40 simultaneously adjusts the valve 41 so as to open the waste pipe 32, thus allowing the water level in the trough to fall and thus empty the basin.

The completed picker unit 46 is shown in Fig. 7. The units 46 are riveted after the unit is moulded to further secure the elements together, after which, the moulded piece is cut along the line 47—47 thus obtaining two complete pickers. The rivets appear at 48.

In practicing my invention, the component parts of the picker are assembled as heretofore described and fastened in proper relationship to each other by means of a tack or other suitable means. This structure is then immersed in hot wax or other impregnating compound until perfectly pliable and flexible. The unit is then placed in position in the moulds, the rounded portion 49 of the structure abutting against the shaping piece 15 and the lugs 50 fitting into the aperture 14', as shown in Fig. 6. The base member 14 is then positioned against the side piece of the mould 7 with the shaping piece abutting against the side wall 44 of the cooling base. The filler member 18 is then positioned through the aperture 51 of the picker and the aperture 14' of the base. The top piece 19 is then positioned over the filler member 18 with the lug 50 of the picker extending into the aperture 19' thereof.

The picker is now positioned correctly in the mould and pressure may now be exerted on the side pieces 9 and 10 by their respective pistons. This is accomplished by raising the lever 38, which, when the element to be moulded is being put in place, is in its downward or exhaust position, to its upward or pressure position. By this means, the pressure existing in pipe 39 is allowed to pass through the valve 37 to the four pressure pipes leading to the cylinders 25 through the check valves 29. Due to this action, the side pieces 9 and 10 close and exert a pressure upon the unit positioned in the mould. The flanges 23 of the top piece 19 cooperate with the grooves 24 in the two side pieces so as to allow the pressure thus exerted to push against the leather in all directions.

During the time that the pistons have come to their full limit of the travel and the picker is compressed to the desired size and shape, and simultaneously with the applying of the pressure, valve 41 has closed the waste pipe 32, thus allowing the water level in the cooling basin to rise to the top of the overflow pipe 36. The water thus flooding the basin cools the pickers. When the pickers have cooled sufficiently to solidify the wax or other impregnating compound that is used, the handle 38 is placed in its lower position, thus

closing the pressure pipe 39 and opening the exhaust pipe 32 to the pipes 22 and, at the same time by means of the linkage 40, has opened the waste pipe 32, the pressure being removed from the cylinders, the side pieces 9 and 10 of the mould are brought back to their original positions away from the moulded picker by action of the springs 21 and 30. Referring specifically to Fig. 3, it may be noted that the springs 43 act to push the bottom piece 14 away from the side piece 7, thus effectively freeing the moulded picker from all the side pieces of the mould. The top piece 19 and the filler member 18 are then removed and the completed picker unit 46 is easily removed. To further secure the elements together, this unit is now riveted, as shown in Fig. 6, by means of the rivets 48. The unit thus formed comprises two pickers and in order to secure the final article, it must be cut along the lines 47-47, thus forming two complete loom pickers.

The flanges 23 of the top piece 19 are wedge shape and the grooves 24 are correspondingly shaped. Hence, the side pieces 7 and 9, when they move together, have the effect of forcing the top piece downward to compress the picker in a vertical direction.

It is to be particularly noticed that in this process, eight pickers are formed in one operation by one attendant in a very short space of time. The unit thus formed can be subjected to any desired pressure and thus be securely and firmly cemented together.

35 It will be understood that the invention is not limited to the specific embodiment shown, and that various deviations may be made therefrom without departing from the spirit and scope of the appended claims.

40 I claim:

1. In a machine for forming loom pickers, the combination of an open-topped cooling basin, a plurality of moulds mounted therein, means adapted to exert a pressure on said moulds, and a cooling system co-operating therewith to circulate the coolant within the basin and about said moulds.

2. In a machine for forming loom pickers, the combination of a cooling basin and a mould mounted therein consisting of a stationary side piece, two pressure-exerting side pieces, a base plate having secured thereon a suitable shaping device, a flanged top piece, and a filler member adapted to co-operate with said base plate and top piece.

3. In a machine for forming loom pickers, the combination of an open-topped cooling basin, a plurality of moulds mounted therein and having movable side pieces, pressure-exerting means consisting of cylinders disposed between adjacent molds, pistons operating therefrom and exerting pressure against the side pieces of said moulds, and a cooling system co-operating therewith for circulating fluid through the basin and about said moulds.

4. In a machine for forming loom pickers, the combination of a cooling basin substantially rectangular in shape, moulds arranged in the four corners thereof adjacent the side walls of said basin, the moulds comprising movable side pieces, resilient means for retracting some of said pieces, and means for actuating said side last-named plates and exerting a pressure thereon. 70

5. A mould for compressing loom pickers consisting of a stationary side piece, two movable side pieces having pressure means co-operating therewith, a yieldable base plate, a shaping piece mounted on the base plate, a flanged top piece co-operating with the stationary side piece and one movable side piece, and a filler member co-operating with and fitting into the groove provided in the top piece and the base plate. 80

6. In a machine for forming loom pickers, the combination of a cooling basin substantially rectangular in shape, moulds arranged in the four corners and secured to the side walls of said basin, springs co-operating with part of the side walls of said moulds whereby said side walls are normally retracted, means for actuating said side plates and exerting a pressure thereon, and a cooling system co-operating therewith to cool the mould after pressure has been applied. 90

7. In a machine for forming loom pickers, the combination of a basin having connections for a cooling medium, a plurality of moulds mounted in the basin, pressure-exerting means consisting of cylinders, pistons operating therefrom, and coacting valves controlling the pressure admitted to the cylinders and the medium for cooling the mould whereby when pressure is exerted on said moulds the cooling medium fills the basin. 95

8. A machine for forming loom pickers, comprising a basin containing a mould for shaping the picker, means for applying pressure to said mould, means for supplying a cooling medium to said basin, means for draining said cooling medium, and means for controlling the first-named means and the draining means so that when said mould is subjected to pressure the draining of the basin is suspended to enable the cooling 100 medium to accumulate therein. 110

9. A machine for forming loom pickers, comprising a mould for shaping the picker, the mould including two relatively movable side pieces, a bottom piece and a shaping piece between the side pieces, a top piece having wedging engagement with the side pieces so that when the side pieces are actuated toward each other the top piece will be forced to compress the picker in a direction transverse to the line of movement of the side pieces, and a third side piece movable in a direction different from that of the first-named side pieces and said top piece. 120

10. In molding apparatus, a plurality of 130

molds having movable side pieces, said molds arranged upon the corners of a polygon, and pressure cylinders disposed between adjacent faces of each pair of molds, each cylinder having a plunger for co-action with the movable side pieces of the molds between which it is arranged.

11. In molding apparatus, a plurality of molds having movable side pieces, said molds arranged upon the corners of a polygon, pressure cylinders disposed between adjacent faces of each pair of molds, each cylinder having a plunger for co-action with the movable side pieces of the molds between which it is arranged, and means for simultaneously actuating the plungers of all of said pressure cylinders.

12. In molding apparatus, a plurality of molds having movable side pieces, said molds arranged upon the corners of a polygon, and means disposed between adjacent faces of each pair of molds and co-acting with the movable side pieces at such faces of each thereof for exerting pressure against the side pieces.

13. A mold comprising a base, stationary and movable side pieces and a top piece, means for moving the movable side piece toward the stationary side piece, and means upon the stationary and movable side pieces co-acting with the top piece for urging the top piece toward the base.
